UNITED STATES PATENT OFFICE.

DAVID M. FERGUS AND JAMES A. GRIFFITHS, OF PHILADELPHIA, PA.

COMBINED EJECTOR AND INJECTOR.

SPECIFICATION forming part of Letters Patent No. 323,503, dated August 4, 1885.

Application filed September 3, 1884. (Model.)

To all whom it may concern:

Be it known that we, DAVID M. FERGUS and JAMES A. GRIFFITHS, citizens of the United States, residing at Philadelphia, in 5 the county of Philadelphia and State of Pennsylvania, have invented certain new and useful Improvements in Combined Ejectors and Injectors; and we do hereby declare the following to be a full, clear, and exact description 10 of the invention, reference being had to the accompanying drawing, which form part of this specification, in which the figure is a longitudinal vertical section of a combined ejector and injector embodying our improvements.

15 Our invention has relation to that class of devices or machines composed of an ejector and injector combined, the former operating to lift fluids and the latter to force the same into a steam-boiler or against pressure.

20 Our improvements have for their object to simplify the construction, to reduce the expense, and increase the efficiency of the machine. Said improvements consist, first, in the peculiar construction of the shell or body 25 of the machine; and, second, in the combination therewith of the other parts, as herein-after fully described and specifically claimed.

Referring to the accompanying drawing, A represents the body or shell of the machine, 30 having a steam-inlet, B, a water-supply pipe, C, an overflow-outlet, D, and a discharge-connection, E, for the boiler. F is a steam-nozzle, and G the combining and discharging tube of the ejector, located in a chamber, C', above 35 the water-supply pipe. H is the steam-nozzle, and I I' the combining and discharging tubes of the injector. K L M are valves, the special 40 purposes and operation of which will herein-after be fully described. In themselves we lay no claim, broadly, to any of the foregoing parts, but only to the special construction hereinafter fully set forth.

N is a pipe cast integral with the body A, and forming an outside connection between 45 the steam-inlet B and the water-chamber C', in which the ejector-tubes are located, said pipe being prolonged into said chamber and carrying the nozzle F. It will be noted that the tubes F and G are in line with the steam- 50 inlet B. In constructing the machine these tubes are passed down through said steam-in-

let and secured, respectively, in the end of pipe N and in the bridge e. To close communication from the steam-inlet B with the interior of the machine, except by way of pipe N, a 55 plug, O, is screwed into the bridge or bearing at o, after the tubes F and G have been inserted.

The injector-nozzle H and the adjacent or receiving end of tube I, as well as the dis- 60 charging-end of tube G, are located in a chamber, P, whose boundaries are the walls of the shell A and the bridges e and o. The inlet for water to this chamber is through the tube G. The outlet is through valve L when the latter 65 is opened, and through tube I when said valve L is closed into another chamber, Q, in which are located the adjacent ends of the tubes I I'.

The method of operation of the machine is as follows: At starting, valve K is closed 70 against the adjacent end of the steam-nozzle H, valve L opened, and valve M pressing against its seat. Steam being admitted through inlet B passes wholly by way of pipe N to the ejector and raises water through supply-pipe 75 C into chamber C'. From the chamber C' the water is ejected into chamber P, completely surrounding and submerging the exposed part of nozzle H and the adjacent end of tube I. The water passes from chamber P through 80 passage p' and valve L into chamber Q, in which latter chamber the discharging end of tube I is located and thence to and out of the overflow-pipe D, the valve M opening automatically. Valve L is now closed, whereupon 85 the water passes from chamber P through tube I and still overflows through pipe D. Valve K is next opened, admitting steam through nozzle H and forcing water from chamber P through the discharging and combining tubes 90 I and I' into the boiler. Valve M then automatically closes, shutting off the overflow. The lifting and feeding operation then proceeds until suspended. Valve M may be dispensed with, if desired, as it is used only to 95 prevent noise.

The provision of the pipe N permits steam to be taken at the top of the machine yet admitted to the ejector below the tubes of the latter. The ejector-tubes being aligned with 100 the steam-pipe may be passed in through the latter, the plug O closing up the entering-

passage and preventing communication except through pipe N. The water-chamber P completely surrounds the nozzle H and the adjacent ends of tubes G and I, so that the 5 water lifted by the ejector submerges the same directly, thus obtaining the best effects for purposes of condensation.

The general construction of the shell permits the body to be made in a single casting, 10 the internal tubes and the valves being easily fitted thereto.

We may substitute for the various tubes F, 15 G, H, I, and I' other tubes of different construction, as our invention is not limited to the said tubes or any particular form thereof, and in case of such change we may substitute for the automatic valve M a globe or other manually-operated valve.

It will be noted that in this invention the 20 ejector is located in a plane below the injector, and that there are two separate and distinct water-chambers connected by a passage-way having a valve, so that in the preliminary lifting the water passes from one of these 25 chambers to the other through said passage, and that when the forcing is going on said passage-way is closed.

What we claim as our invention is as follows:

30 1. In a combined ejector and injector, the combination, with the ejector-chamber C', of the pipe N, arranged as shown, cast integral with the body or shell and extended or projected into said chamber and carrying the 35 steam-nozzle F, said nozzle being above the water-supply pipe C and aligned axially therewith, substantially as shown and described.

2. In a combined ejector and injector having the ejector located below the injector, and

the tubes of the former transverse to the axial plane of the latter, both being contained in a single shell or body, a water-chamber, P, having for its boundaries the walls of the shell and the two bridges which sustain the combining and discharging tubes of the ejector and injector, the discharging end of the ejector-tube, the steam-nozzle of the injector, and the receiving end of the injector combining tube being located in said chamber, substantially as shown and described. 45 50

3. In a combined ejector and injector having a water-chamber, P, in which are located the discharge end of the ejector-tube, the receiving end of the injector combining tube 55 and the injector-nozzle, the combination, with said chamber and the chamber Q, in which is located the discharging end only of the injector-tube I, of a passage, p', and valve L, whereby the lifted water is caused to be directly discharged from the ejector on the injector-tubes and to submerge the latter, and the passage-way between said chambers opened in the preliminary lifting and closed when the injector is forcing, substantially as shown 60 65 and described.

4. In a combined ejector and injector in which the ejector-tubes are aligned with the steam-inlet of the machine, the plug O, which closes up the entrance-opening for said tubes, 70 substantially as shown and described.

In testimony that we claim the foregoing we have hereunto set our hands this 27th day of August, 1884.

DAVID M. FERGUS.
JAMES A. GRIFFITHS.
